UNITED STATES PATENT OFFICE.

EMIL M. BREMER, OF GLENVILLE, MINNESOTA.

ATTACHMENT FOR GAS-ENGINE COOLING SYSTEMS.

Application filed January 21, 1925. Serial No. 3,819.

This invention relates to a device particularly adapted for use as an anti-freeze attachment for radiators such as are employed to cool the cooling medium of internal combustion engines, and more particularly relates to such a device adapted for use on automobile radiators to prevent the lower portion or outlet thereof from freezing in extremely cold weather especially after the automobile has been started.

In the operation of automobiles in cold weather, it is well-known that difficulty is often experienced in preventing the lower portion of the radiator or circulating system from freezing, especially when the circulation through the radiator is obtained by the thermo-siphon principle, used in numerous makes of automobiles. As the water or other cooling medium flows through the radiator, it rapidly cools, sometimes to the extent that when it reaches the outlet at the bottom of the radiator, it will freeze and obstruct the flow therethrough, thereby causing the water in the cylinder jacket to be heated to the boiling point after which it will rapidly be dissipated in the form of steam through the usual overflow pipe provided in the radiator. It is, therefore, desirable that means be provided whereby the water will be prevented from freezing in the lower portion of the radiator and thus obstructing the flow of water therethrough, and it is the object of this invention to provide a simple and efficient method and means whereby the frozen section of the system will immediately be thawed by the steam generated in the system, as a result of the obstruction caused by the frozen portion.

A further and more specific object of the invention is to provide a steam jacket around the outlet pipe of the radiator which has a connection with the usual overflow pipe of the radiator so that steam escaping through the overflow pipe will be discharged into the steam jacket, thereby thawing out the frozen section of the radiator.

A further object of the invention is to provide a simple and inexpensive anti-freeze attachment for a gas engine cooling system, and particularly the radiator of an ordinary automobile, which may easily and quickly be attached thereto in cold weather and readily be detached therefrom, when desired, as in warm weather when there is no use for the device.

Other objects of the invention will appear

from the following description and the accompanying drawings and will be pointed out in the annexed claims.

In the drawings, there has been disclosed 60 a structure designed to carry out the various objects of the invention, but it is to be understood that the invention is not confined to the exact features shown as various changes may be made within the scope of 65 the claims which follow.

In the accompanying drawings forming a part of this specification,

Figure 1 is an elevation of a radiator showing the invention applied thereto; 70

Figure 2 is a vertical sectional view on the line 2—2 of Figure 1 showing the steam jacket enclosing the lower portion or outlet of the radiator;

Figure 3 is a detail sectional view on the 75 line 3—3 of Figure 2.

In the selected embodiment of the invention here shown, there is illustrated a radiator of ordinary construction, comprising the upper water chamber 4, lower water 80 chamber 5 and the cooling tubes 6 interposed therebetween to provide communication between the two chambers. The usual overflow pipe 7 is also shown and has its upper end terminating within the filler neck 8 of the 85 radiator. An elbow 9 is secured to the bottom wall of the lower water chamber 5 to provide an outlet for the water, a hose connection 11 being secured to the end of the elbow to preferably provide a flexible connection between the radiator and the engine water jacket, (not shown). The usual inlet connection 12 is shown depending from the upper water chamber 4 and this connection is also adapted to be connected to the water 90 jacket of the engine. 95

A feature of this invention resides in the novel means provided for thawing out the lower portion or outlet elbow 9 of the radiator should it be obstructed by water 100 freezing therein in cold weather. Such means preferably consists in the provision of a steam jacket or casing 13, preferably of a flexible material, which is so arranged as to substantially enclose the lowermost portion of the elbow 9, as shown in Figures 1 and 2. This jacket is suitably secured to the elbow by means of a bracket 14 securely clamped to the elbow 9 preferably by means of a clamping bar 15 and bolts 16 (see Figure 3). The bracket 14 is shaped so as to clamp the upper edge of the flexible jacket 105 110

or casing against the usual flange of the elbow 9, a portion of it also being securely clamped against the inwardly extending neck portion thereof.

5 A flexible hose connection 17 has one end secured to the jacket and the other end connected to the lower end of the overflow pipe 7 thereby establishing communication between the jacket and the interior of the upper portion of the water chamber 4 of the radiator. Thus it will be seen that any steam or water overflowing from the water chamber 4 through the overflow pipe 7 will be discharged into the chamber provided around the outlet elbow 9 by means of the steam jacket or casing 13. An opening is provided in the lower portion of the casing 13 to provide clearance for the usual drain cock 18, and this opening is preferably of such size as to permit the live steam being discharged into the casing to escape therethrough as indicated by the arrows in Figure 1, thereby providing free circulation of steam around the lower portion of the elbow 9.

From the foregoing, therefore, it will be readily seen that by the employment of this novel method and means for preventing the lower portion or outlet of a radiator from freezing, the usual danger of radiators freezing in cold weather will be practically eliminated. Should the outlet 9, however, freeze, and the passage of water therethrough be obstructed by ice, such obstruction will immediately cause the water in the cooling jacket of the engine to be generated into steam, which will be discharged through the overflow pipe 7 into the chamber provided around the elbow by the jacket or casing 13 resulting in immediately thawing the frozen section and re-establishing circulation through the radiator.

The construction of this novel device is very simple and inexpensive, and is such that it may easily and quickly be attached to the radiator of an ordinary automobile and may as readily be removed therefrom when not needed, as in warm weather. As a result of the jacket 13, preferably, being constructed of a flexible material, it may conveniently be folded and packed into a comparatively small space in the tool box of the automobile or other suitable place,

when not in use. If desired, however, the jacket 13 may be permanently left on the outlet elbow of the radiator and only the hose connection 17 be detached, when the device is not in use.

I claim as my invention:

1. In combination with a radiator, including an overflow pipe and outlet connection, a bulging, flexible pendant jacket surrounding and detachably secured along its upper periphery only to the connection and forming a steam chamber therebeneath, said jacket having a flexible conduit connected with the overflow pipe, and having a discharge opening at its lowermost point.

2. In combination with a radiator, including an overflow pipe, and having an outlet elbow vertical and bend portions and further having a drain-cock, a substantially semi-spherical element of flexible, collapsible material, of small dimension, arranged beneath the elbow in bulging, bagging relation to form therewith a steam chamber beneath the vertical and bend portions of said elbow, and having a drain opening through which the cock extends and of greater diameter than the cock, and an annular member compressibly forcing said element peripherally of its upper side, against the elbow, to seal that side, said annular member being introduced from below.

3. In combination with a radiator, including an overflow pipe, and an outlet elbow having a drain-cock and having a longitudinally disposed portion, a bulbous substantially semi-spherical element of flexible, collapsible material, arranged beneath the elbow in bulging spaced relation thereto to form therewith a steam chamber, and having a drain opening through which the cock extends, said opening of greater diameter than the cock, and an annular member clampingly engaging laterally against and along the upper periphery of the element, and having intermediately disposed lateral ears, a cross member resting upon the top of the longitudinal portion of the elbow, and bolts traversing cross member and ears and drawing said annular member upwardly.

In witness whereof, I have hereunto set my hand this 17th day of January, 1925.

EMIL M. BREMER.
